UNITED STATES PATENT OFFICE.

SAMUEL LANCET, OF BROOKLYN, NEW YORK, ASSIGNOR TO COSMOPOLITAN WAREHOUSES, INC., OF NEW YORK, N. Y., A CORPORATION OF NEW YORK.

DESIGN FOR A BOTTLE.

Application filed January 26, 1929. Serial No. 29,784. Term of patent 7 years.

To all whom it may concern:

Be it known that I, SAMUEL LANCET, a citizen of the United States, residing at Brooklyn, in the county of Kings and State of New York, have invented a new, original, and ornamental Design for a Bottle, of which the following is a specification, reference being had to the accompanying drawing, forming part thereof.

Fig. 1 is a top plan view of a bottle embodying the design constituting the present invention;

Fig. 2 is a front elevational view of the said bottle; and

Fig. 3 is a rear elevational view of the same.

I claim:

The ornamental design for a bottle, as shown.

SAMUEL LANCET.
